UNITED STATES PATENT OFFICE

SAMUEL SHAFER, JR., OF MILWAUKEE, WISCONSIN, ASSIGNOR TO CHAIN BELT COMPANY, OF MILWAUKEE, WISCONSIN, A CORPORATION OF WISCONSIN

CONVEYER CHAIN

Application filed November 6, 1931. Serial No. 578,489.

This invention relates to conveyer chains and more particularly to the type which carries a series of rollers mounted with their axes longitudinal of the links whereby the materials to be transported may be loaded upon and discharged from the conveyer through movement transverse to the line of travel thereof. Such conveyers are commonly employed in double lines or strands for handling lumber and the like although they are not limited solely to such use.

The invention has for one of its objects to provide a device of this character which will be simple in construction, comparatively inexpensive to manufacture and more efficient in use than those which have been heretofore proposed.

In my prior U. S. Patent No. 1,745,192 granted January 28, 1930 entitled Transverse conveyers, I have described and claimed a conveyer chain of this type in which the links are formed of malleable iron castings and in which alternate links carry a single longitudinally disposed roller, a portion of which projects over the next adjacent, non-roller carrying link. While the present invention may likewise be applied to a cast chain, it lends itself readily to employment with a drop forged chain which, as is well known by those skilled in the art, possesses considerably greater strength than cast chain with less weight, and is less subject to breakage. The present invention constitutes a further improvement over that of my said prior patent in that a single support for the rollers is integrally formed with certain of the links in the drop forging process, and a roller is rotatably mounted at either end of the said support, one of said rollers or a portion of both rollers projecting over the next adjacent non-roller carrying link or links so that when the chain is made up of alternate roller-carrying and non-roller carrying links a substantially continuous load receiving roller surface is presented upon which the load may be charged through transverse movement.

With the above and other objects in view which will appear as the description proceeds, the invention consists in the novel details of construction and combinations of parts more

fully hereinafter described and particularly pointed out in the appended claims.

Referring to the accompanying drawing forming a part of this specification in which like reference characters designate like parts in all the views:

Figure 1 is a side elevational view partly in section of a portion of a conveyer chain constructed in accordance with the present invention;

Figure 2 is a top plan view of the parts shown in Figure 1, certain of the rollers being omitted and other portions being shown in section;

Figure 3 is a detail perspective view of one of the roller-carrying links as shown in Figures 1 and 2; and

Figure 4 is a sectional elevational view through a roller-carrying link of slightly modified construction.

Referring more particularly to the said drawing, 5 indicates generally a sprocket chain of a well known drop forged type which is made up of alternate single bar links 6 and spaced double bar links 7. The said links are provided with horizontal longitudinal slots 8 and 9 respectively and are pivotally connected together by the chain pins or pintles 10 provided with the heads 11, which are normally retained in place by lugs 12 and 13 formed upon the double bar links in the process of drop forging.

Certain or all of the single bar links 6 are provided with a single roller support 15 which may be formed integrally with the said links in the process of drop forging and in the form shown in Figures 1, 2 and 3 the said supports extend substantially perpendicularly outward from the said links at one end thereof. The supports 15 are provided with a longitudinal bore 16 which receives a spindle 17 extending through the support and projecting from either end thereof as clearly shown in Figures 1 and 2. The said spindle may be retained in place within the support in any suitable manner, as for example by means of the transverse locking pin 18.

Upon the projecting ends of the spindle 17 there are rotatably mounted the load-receiving rollers 19 and 20, the rotative axes 100

of which of course are substantially longitudinal with respect to the links 6. The rollers may be retained in place by any suitable means, as for example by heading the ends 5 of the spindle 17 as indicated at 21.

As will be clear from Figure 1 the rollers 19 and 20 are located in a plane above that of the chain links and the rollers 19 extend over the links 7 while the rollers 20 overlie 10 the links 6. While obviously it is not necessary to provide each link 6 with a support 15 and rollers 19 and 20 it is preferred to do so, and when such construction is employed there is presented a substantially continuous load- 15 supporting roller surface which greatly facilitates the loading and unloading of material upon or from the conveyer strands through transverse sliding movements of the material, as will be readily understood by 20 those skilled in the art. The rollers 19 and 20 as shown in Figures 1 and 2 may be hollowed out to provide internal chambers 23 for the reception of lubricant which may be introduced through a filling opening 24, see 25 Fig. 2, which opening may be normally closed by a threaded plug 25.

Instead of forming the support 15 at the extreme end of the links 6 said support may be positioned intermediate the ends at sub- 30 stantially the mid-portion as indicated in Figure 4, in which event a portion of each of the rollers 19 and 20 will overlie the carrying links 6 while other portions constituting the extreme outer ends of the rollers will of course 35 overlie portions of the adjacent non-roller carrying links 7 as will be readily understood. In the form shown in Figure 4 the spindle 17 is illustrated as provided with a tapering mid-portion 17' receivable in the bore 16 of 40 the support 15 for positioning and seating the said spindle in the support.

It is obvious that those skilled in the art may vary the details of construction as well as the precise arrangement of parts without 45 departing from the spirit of the invention, and therefore it is not wished to be limited to the above disclosure except as may be required by the claims.

What I claim is:

50 1. A conveyer chain, certain of the links of which are provided with a single projecting support; and a load receiving roller rotatably carried by said support at each end thereof with their axes substantially longitudinal of the link.

55 2. A conveyer chain, certain of the links of which are provided with a single projecting support; a spindle carried by and projecting beyond the respective ends of said support, the axis of said spindle being substantially longitudinal of the link; and a roller carried by each projecting portion of said spindle.

60 3. A conveyer chain, certain of the links 65 of which are provided with a single pro-

jecting support; a spindle carried by and projecting beyond the respective ends of said support, the axis of said spindle being substantially longitudinal of the link; and a roller carried by each projecting portion of at least one of said rollers overlapping the next adjacent link. 70

4. A conveyer chain comprising alternate single-bar and double-bar links, certain of said single-bar links having a single support 75 extending therefrom substantially perpendicular to the line of travel; and a roller rotatably carried by said support at each end thereof, at least a portion of at least one of said rollers overlapping an adjacent double-bar link. 80

5. A conveyer chain comprising pintle connected alternate single-bar and double-bar links, each of said single bar links having a single support extending vertically therefrom; and a load-receiving roller rotatably carried by said support at each end thereof, the axes of said rollers being substantially 85 longitudinal of the link. 90

6. A conveyer chain comprising alternate single-bar and double-bar links, each of said single-bar links having a single support extending from one end thereof; and a roller rotatably carried by said support at each end thereof, one of said rollers being positioned adjacent the single-bar link and the other roller being adjacent the next double bar link. 95

7. A drop-forged conveyer chain, certain of the links of which have a single support 100 extending from one end thereof; and a roller rotatably carried by said support at each end thereof, one of said rollers being positioned adjacent the link which carries it, and the other roller being adjacent the next non-roller-carrying link. 105

8. A drop-forged conveyer chain, the alternate links of which have a single support extending outwardly from one end thereof; and a roller rotatably carried by said support at each end thereof in a plane above that of the link, one of said rollers being in transverse alinement with the carrying link, and the other roller being in transverse alinement with the next adjacent non-roller carrying link. 116 115

9. A drop-forged conveyer chain, the alternate links of which have a single support extending vertically from one end thereof; and a roller rotatably carried by said support at each end thereof, the axes of said rollers being substantially longitudinal of the link, and one of said rollers overlying the carrying links, while the other of said rollers overlies the next adjacent non-roller carrying link. 120 125

10. A drop-forged conveyer chain, certain of the links of which have a single support extending outwardly from a point between the ends thereof; and a roller rotatably car- 130

ried by said support at each of its ends, a portion of each of said rollers being adjacent the carrying link, and another portion of each roller being adjacent a contiguous non-roller carrying link.

5 11. A drop forged conveyer chain, the alternate links of which have a single support extending substantially perpendicularly from the mid-portion thereof; and a roller rotatably carried by said support at each of its ends, a portion of each of said rollers overlying the carrying link, and another portion of each roller overlying a contiguous non-roller carrying link.

10 12. A conveyer chain, certain of the links of which have a single support extending outwardly therefrom; and a roller rotatably carried by said support and at least a portion thereof overlying said link, and its axis being substantially longitudinal of said link.

15 13. A conveyer chain, certain of the links of which have a single support extending outwardly therefrom; and a roller rotatably carried by said support and at least a portion thereof overlying an adjacent non-roller carrying link, the axis of said roller being substantially longitudinal of said link.

20 14. A link for conveyer chains having a single support for a longitudinally disposed roller projecting therefrom.

25 15. A link for conveyer chains having a single support for a longitudinally disposed roller projecting from one end thereof.

30 16. A link for conveyer chains having a single support for a longitudinally disposed roller projecting from a point intermediate the ends thereof.

35 17. A drop-forged link for conveyer chains having a single rigid support projecting perpendicularly therefrom and provided with a bore to receive a longitudinal roller-carrying spindle.

40 In testimony whereof, I affix my signature.
